UNITED STATES PATENT OFFICE

LEO J. WAHL, OF STERLING, ILLINOIS, ASSIGNOR TO WAHL CLIPPER CORPORATION, OF STERLING, ILLINOIS, A CORPORATION OF ILLINOIS

BLADE ATTACHMENT FOR CLIPPERS

Application filed September 20, 1929. Serial No. 323,931.

My invention relates to hair clippers and more particularly to a blade attachment for electrically operated clippers of the type shown in the Wahl patents —————.

It is the principal purpose of this invention to provide an attachment which can be applied to clipper blades to increase the effective width of the stationary blade and thereby make it possible to change quickly from a relatively fine cutting blade to a comparatively coarse cutting blade.

I will describe one form which my invention may take by reference to the accompanying drawings wherein —————

15 Figure 1 is a side view of a clipper equipped with my attachment;

Figure 2 is a section on line 2—2 of Figure 1;

20 Figure 3 is a section on line 3—3 of Figure 2; and

Figure 4 is a perspective view of the clipper attachment removed from the regular blade.

Referring now in detail to the drawings I 25 show at 5 a clipper such as that shown in my patent above mentioned, which clipper has the movable blade 6 and stationary blade 7 as is common in such devices.

The stationary blade 7 is somewhat different from the standard stationary blade in that it is tapered on both faces 8 and 9 so as to be relatively thick at the back end. The purpose of this tapering is to give a fairly steep cone surface on the bottom of the stationary blade and yet to retain a flat slope on the top of the blade where the moving blade rides thereover so as to make it easier to attain the proper contact between the moving blade and stationary blade.

40 As will be clear from an inspection of my prior patent these clippers operate by means of a harmonically reciprocating arm which is connected to a movable blade at any end and relatively fixed at the other end. This, 45 of course, means that the movable blade is moving more or less on the arc of a circle and the nearer the plane of the surface on which the movable blade rides can be brought into parallelism with the plane in which the reciprocating drive operates the less difficulty will

be experienced in maintaining proper contact between the stationary and moving blade.

The tapering of the blade 7, as has been designed, serves in some degree to tend to establish the right relation in this respect.

Now the blade 7 on its opposite sides is cut away as shown at 10 and 11 to provide a pair of tracks which are defined by shoulders at 12 and 13 on the inside. The attachment, by means of which the stationary blade is made effectively thicker, consists of the plate 14 provided with relatively coarse long cutting teeth 15, adapted when it is in position to project somewhat beyond the teeth on the stationary blade 7.

The attachment has at its opposite sides the spring arms 16 and 17 bent upwardly and then back in substantial parallelism with the main body portion thereof so that they extend well forward toward the front of the attachment. These arms 16 and 17 are preferably depressed slightly at their free ends, as indicated at 18 and 19, so as to obtain a good spring grip on the guide surfaces 10 and 11 of the stationary blade 7.

These free ends of the arms 16 and 17 are also preferably directed slightly toward each other so as to be closer together at their free ends than at their point of attachment with the main body 14 so that when they are applied on the stationary blade 7 they will press inwardly against the shoulders 12 and 13 also. In this manner a very snug and tight fit may be obtained between the attachment and the blade so that it will not shake loose during use. The attachment is, of course, perfectly aligned by means of the surfaces provided on the stationary blade 7 so that all that is necessary is to merely slip it onto the stationary blade whenever it is desired to use it.

A suitable finger piece 20 is mounted on the arm 16 for convenience in applying the attachment to the stationary blade. This attachment may of course be adjusted endwise relative to the stationary blade so as to lengthen or reduce the cut without in any way of interfering with its operation and this can be done by the operator without stopping the clipper by merely pressing the finger piece one way or the other.

From the above description it is thought that the construction and operation of this device will be clear to those skilled in this art.

Having thus described my invention what I claim as new and desire to secure by Letters Patent is:

1. Adjusting means for clippers for increasing the effective thickness of the stationary blade comprising longitudinal 10 grooves on the top of the stationary blade and an auxiliary blade having spring arms projecting over the back of the stationary blade and extending forwardly in said grooves whereby to hold the auxiliary blade 15 in position.

2. Adjusting means for clippers for increasing the effective thickness of the stationary blade comprising longitudinal 20 grooves on the top of the stationary blade and an auxiliary blade having spring arms projecting over the back of the stationary blade and extending forwardly in said 25 grooves whereby to hold the auxiliary blade in position, said stationary blade being wedge-shaped in longitudinal cross section.

3. Adjusting means for clippers for increasing the effective thickness of the stationary blade comprising longitudinal 30 grooves on the top of the stationary blade and an auxiliary blade having spring arms projecting over the back of the stationary blade and extending forwardly in said 35 grooves whereby to hold the auxiliary blade in position, said spring arms pressing downwardly in said grooves and also laterally in opposite directions whereby to prevent lateral play of said auxiliary blade.

4. Adjusting means for clippers for increasing the effective thickness of the stationary blade comprising longitudinal 40 grooves on the top of the stationary blade and an auxiliary blade having spring arms projecting over the back of the stationary blade and extending forwardly in said 45 grooves whereby to hold the auxiliary blade in position, said grooves being on the opposite side edges of said stationary blade.

5. Adjusting means for clippers for increasing the effective thickness of the stationary blade comprising longitudinal 50 grooves on the top of the stationary blade and an auxiliary blade having spring arms projecting over the back of the stationary blade and extending forwardly in said 55 grooves whereby to hold the auxiliary blade in position, said grooves being on the opposite side edges of said stationary blade, and said spring arms pressing inwardly 60 against the adjacent side walls of said grooves.

6. Adjusting means for clippers for increasing the effective thickness of the stationary blade comprising longitudinal 65 grooves on the top of the stationary blade and an auxiliary blade having spring arms

projecting over the back of the stationary blade and extending forwardly in said grooves whereby to hold the auxiliary blade in position, one of said arms carrying an upstanding finger piece for changing the 70 position of said auxiliary blade.

7. A stationary blade for hair clippers which is wedge-shaped from the teeth to the back end, and which has on the top surface thereof a pair of grooves the bases of which are substantially parallel with the lower surface thereof.

8. A stationary blade for hair clippers which is wedge-shaped from the teeth to the back end, and which has on the top surface thereof a pair of grooves the bases of which are substantially in alignment with the lower surface thereof, and an auxiliary blade having spring arms fitting in said 80 grooves.

In witness whereof, I hereunto subscribe my name this 3rd day of Sept., A. D., 1929.

LEO J. WAHL.
